UNITED STATES PATENT OFFICE.

WILLIAM E. WILSON, OF AKRON, OHIO.

PUTTY CLIP.

Application filed December 19, 1919. Serial No. 346,000.

To all whom it may concern:

Be it known that I, WILLIAM E. WILSON, a citizen of the United States, residing at Akron, in the county of Summit and State of Ohio, have invented certain new and useful Improvements in a Putty Clip, of which the following is a specification.

This invention relates to a putty clip to be especially used upon what is commonly known as the spiral putty or legging which is provided at its top end with an elongated tape or strip.

The principal object of the invention is to provide a clip which may be attached so as to hold the tape of the putty or legging securely around the wearer's leg so as to prevent same from slipping or becoming accidentally removed as has been the experience of leggins of this nature.

Another object of this invention is to provide a clip of a very simple construction which will be small in size so as not to be readily noticed when worn and will not have a tendency to tear the tape when attached theron.

With these and other objects in view, this invention consists of certain novel constructions, arrangements, and combinations of parts that will be hereinafter more fully described.

In the accompanying drawings:

Figure 1 shows the device in use.

Fig. 2 is a perspective view of the invention showing part of the clamp broken away so as to more clearly understand the construction of the body portion; and

Fig. 3 is a fragmentary view showing the interior construction of the clamp.

By referring to the accompanying drawings by numerals it will be seen that in Figure 1 there is shown the spiral putty 1 wrapped around the leg of the wearer and having at its top the tape 2 upon which is fixed the clamp indicated by the letter c.

Coming now more particularly to the invention which is shown to advantage in Fig. 2 of the drawing, it will be seen that it consists of a body portion 3 which is of a substantially rectangular shape and has provided the elongated slot 4 spaced a distance

from its free end. Within the slot 4 and running along the longitudinal edge is provided a plurality of teeth 14 for a purpose to be hereinafter described. Along the lon-

55
gitudinal edges of the body 3 there is provided the flanges 5 which extend therefrom at right angles. Along the top longitudinal edge of the body 3 there is provided the spaced apart ears 6 which are bent over upon themselves so as to form the 60 sleeves 7 for receiving a pin 15. Along the bottom edge of the flange 5 it will be noticed there is provided a cut-away portion 11 for a purpose soon to be disclosed.

A clamp 8 of a substantially rectangular 65 shape is provided and has an ear at one end bent upon itself so as to form a sleeve 9 fitting between the sleeves 7 and around the pin 15. At the other opposite edge of the clamp 8 there is provided a spring cap 10 70 which is adapted to engage the cut-away portion 11 of the flange 5.

Upon the inner surface of the clamp 8 there is provided a block 12 which is held thereto by means of the rivet 13. This block 75 12 may be of any suitable frictional material, such as rubber, canvas, and it also may be of metal provided with a friction surface, as is made clear in Fig. 3 of the drawing. I wish to reserve the broadest latitude as far 80 as materials are concerned for this block 12.

By referring to Fig. 1 of the drawing the operation of the device will be clearly seen. The tape 2 is first passed through the slot 4 and then passed around the leg so as to allow 85 the end to be placed between the body portion 3 and the clamp 8. The clamp 8 is then thrust inwardly toward the body 3 so that the spring caps will engage the portion 11. It will, of course, be understood that the 90 putty clip described is especially adapted to be used for the right leg and that the clip used for the left leg is substantially of the same construction with the exception that the ears 6 are placed upon the bottom longitudinal edge of the body and the cut-away portion 11 is placed upon the upper longitudinal portion.

The above description and drawing refer to what I call the preferred form of my invention and I wish it understood that I may make such changes in construction, arrangement, and combination as fall within the scope of the appended claim.

Having thus fully described my invention, 105 what I claim as new and desire to secure by Letters Patent, is:

A device of the class described comprising

a body having a slot adjacent one end, right angularly extending flanges along its longitudinal edges, one of said flanges extending throughout the length of the body and the other terminating a distance from one end thereof, a clamp hinged on the edge having the shorter flange adjacent the termination

thereof, the width of the clamp being less than the length of the body, so that the clamp does not extend over the slot.

WILLIAM E. WILSON.
